US00D859388S

(12) **United States Design Patent** (10) **Patent No.:** **US D859,388 S**
(45) **Date of Patent:** **** Sep. 10, 2019**

(54) **CASE FOR MOBILE PHONE**

(71) Applicant: **Samsung Electronics Co., Ltd.**, Suwon-si (KR)

(72) Inventors: **Chong-Yoon Chung**, Seoul (KR); **Ji-Su Hwang**, Seoul (KR); **Hae-Sung Park**, Seoul (KR); **Hyoungh-Shin Park**, Seongnam-si (KR); **Yun-Jin Kim**, Seoul (KR)

(73) Assignee: **SAMSUNG ELECTRONICS CO., LTD.**, Suwon-si (KR)

(**) Term: **15 Years**

(21) Appl. No.: **29/605,228**

(22) Filed: **May 24, 2017**

(30) **Foreign Application Priority Data**

Dec. 9, 2016 (KR) 30-2016-0059963

(51) **LOC (12) Cl.** **14-03**

(52) **U.S. Cl.**

USPC **D14/250**

(57) **CLAIM**

The ornamental design for a case for mobile phone, as shown and described.

DESCRIPTION

FIG. 1 is a front perspective view of a case for mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is an exploded front perspective view thereof showing a mobile phone to provide example environment.

The broken line portion of the case for mobile phone forms no part of the claimed design. The broken lines depicting a mobile phone in FIG. 9 illustrate environmental subject matter that forms no part of the claimed design.

1 Claim, 7 Drawing Sheets
